UNITED STATES PATENT OFFICE.

JAMES F. CRAVEN, OF PITTSBURGH, PENNSYLVANIA.

RAILWAY-RAIL FASTENER.

1,224,608.

Specification of Letters Patent.

Patented May 1, 1917.

Application filed August 7, 1916. Serial No. 113,519.

To all whom it may concern:

Be it known that I, JAMES F. CRAVEN, a resident of Pittsburgh, in the county of Allegheny and State of Pennsylvania, have ⁵ invented a new and useful Improvement in Railway-Rail Fasteners, of which the following is a specification.

This invention relates to driven fastening devices, such as railway spikes or like rail ¹⁰ fastening devices.

The object of the invention is to provide a simple form of interlocked spikes which will be much more firmly held in the tie than railway spikes as ordinarily constructed and ¹⁵ driven and therefore not so liable to pull out or become loose. The invention comprises a pair of spikes together with means serving to guide the spikes when being driven so that one will enter the tie at an inclination ²⁰ to the other, so that the complete spiking device engages a wider area of the tie at its lower end than at its upper end, and therefore can not be withdrawn as a whole from the tie and can not so readily work loose ²⁵ in service.

In the accompanying drawings, Figure 1 is a sectional view through a railroad rail, tie, tie plate and the spiking device, showing the latter in side elevation; Fig. 2 is a ³⁰ horizontal section on the line 2—2, Fig. 1; Fig. 3 is a side elevation of the guiding member and partial section of a tie plate; Fig. 4 is an edge elevation of the same; Fig. 5 is a side elevation of a modified form of ³⁵ guiding member; Fig. 6 is an edge elevation of the same; Fig. 7 is a side elevation of a modified form of guiding member without prongs; Fig. 8 is a sectional view similar to Fig. 1 showing the guiding means formed ⁴⁰ in the tie plate; Fig. 9 is a plan view of the tie plate shown in Fig. 8; and Fig. 10 is a plan view of the heads of a pair of spikes.

In the drawings, 1 represents a wooden ⁴⁵ railway tie, 2 a tie plate, and 3 a standard rail having the usual flanged base 4. 5 and 5^a represent a pair of spikes which may be of substantially the form of standard spikes, but which are shorter than the usual stand- ⁵⁰ ard spikes and each having a head of the same general design as on ordinary railroad spikes, the same overhanging or projecting mostly on one side of the shank, the head 6 of the spike 5 having the standard angle of ⁵⁵ the head to the shank, while the head 6^a of

spike 5^a has the overhanging portion of its head at a less obtuse angle to the shank than has the spike 5. Preferably, also, one side of the head of each of the spikes is slightly flattened off, as shown at 7, Fig. 10, in order ⁶⁰ to permit the spikes to be driven closely together.

Coöperating with these spikes is a suitable spike guiding member 9 which preferably is formed by forging but may be made in ⁶⁵ any other suitable way. This guiding device has a relatively thin web or body portion and with flanges projecting in opposite directions from its inner and outer edges and forming between them grooves or channels to guide the spikes. The flanges 10 and 11 projecting in one direction are preferably vertical so as to form a vertical spike guiding groove 12 for the spike 5 which is to be driven substantially vertically, while ⁷⁰ the flanges 10^a and 11^a on the opposite sides are inclined inwardly, that is, in the direction underneath the rail seat, so as to form an inwardly inclined guiding groove 12^a for the spike 5^a. ⁷⁵

The vertical flanges 10 and 11 may be extended downwardly below the body of the member 9 to form prongs 10^b and 11^b as shown in Fig. 5, for entering the tie and holding the member 9 in place when starting the spikes, but preferably the holding means comprises a projection 9^a of the web of the member 9 as shown in Fig. 4. ⁸⁰

The tie plate 2 of Fig. 1 will be provided with the usual spike holes 14, except that ⁸⁵ these will be made somewhat larger than ordinarily in order to accommodate the two spikes and the spike guiding member 9.

In applying the rail fastening means the spike 5 may be first partially driven in, ⁹⁰ but not so far that the distance between its head and the tie will be less than the height of the guiding member 9, after which the guiding member 9 is then put in place against the spike 5 with the groove 12 engaging said spike, or the member may first be driven down until its prongs 9^a or 10^b and 11^b are embedded in the tie after which the spike 5 is driven in, and then the other spike 5^a is made to engage the inclined ⁹⁵ groove 12^a and is driven in until its head is flush with the head of the spike 5, after which both spikes together are driven in ¹⁰⁰ simultaneously.

When driven fully in the lower ends of the ¹¹⁰

two spikes are considerably spread apart, thus engaging a wider area of the tie at their lower ends than at their upper ends so that as a consequence they can not be withdrawn simultaneously from the tie and consequently can not pull out or work loose under the bending stresses of the rail, as any tendency of the rail to draw out one of the spikes must necessarily exert an equal stress upon the other spike. In this way a very secure fastening means is provided.

Spikes 5 and 5^a can be made by the ordinary method of making standard railway spikes, and differ from the ordinary railway spikes only in the fact that they are shorter, and hence collectively not much heavier than a single standard spike, and the fact that the head of spike 5^a is bent at a lesser angle to its shank than the heads of standard spikes. These spikes can be fabricated at the same tonnage cost as standard spikes. The guiding member 9 is a simple member which can be formed at a single drop-forging operation, and is of light weight and hence not costly.

Figs. 8 and 9 show a modification in which the spike guiding means is formed in the tie plate. As shown the tie plate 2^a is thickened at the points where the spike holes are formed, and each spike hole has two portions, to-wit, a straight through portion 14^a for guiding the spike 5 in vertical position, and an inclined portion 14^b for guiding the spike 5^a into inwardly inclined position. By thickening the plate at the portions where the holes are formed, the walls of the holes will have sufficient depth to form effective guides for the spikes.

What I claim is:—

1. A spike guide comprising a member adapted to be positioned between two spikes and having on opposite sides guides

for said spikes, one of said guides being inclined at an angle to the other guide.

2. A spike guide comprising a member 45 adapted to be positioned between two spikes and provided on opposite sides with guides for the spikes, one of said guides being vertical and the other being inclined relative thereto.

3. In rail fastening means, the combination of a member having two guides, one of which is inclined relatively to the other, and two headed drawn members guided thereby respectively into different inclined positions.

4. In rail fastening means, the combination of a member having two guides side by side, one of which is vertical and the other of which is inclined, and two drawn headed members guided thereby respectively into vertical and inclined positions.

5. In a driven fastening device the combination of a member having guides on opposite faces, one of said guides being inclined relatively to the other, and two headed members adapted to be driven into place on opposite sides of said member and guided thereby respectively into different inclined positions.

6. In a driven fastening device, the combination of a member provided with guides on its opposite faces, one of said guides being vertical and the other being inclined, and two headed members adapted to be driven into place on opposite sides of said member and guided thereby respectively into vertical and inclined positions.

In testimony whereof, I have hereunto set my hand.

JAMES F. CRAVEN.
